IRONING TABLE WITH VARIABLE CONTOUR
Ralph R. Olswang, Scarsdale, N.Y., assignor to Kamkap,
Inc., New York, N.Y., a corporation of New York
Filed July 17, 1959, Ser. No. 827,807
2 Claims. (Cl. 38—138)

This invention relates to ironing table tops for hand ironing and provided with a working area having two different contours and with means for instantly changing from one contour to the other.

An ironing board for ironing large flat articles like sheets and bed spreads should preferably be of rectangular shape with parallel longitudinal edges so that the flat articles being ironed can be progressively moved as they are ironed. The rectangular ironing table top is more suitable for all flat articles regardless of size. Many of the articles ironed in the home are of tubular shape or of an irregular shape with cavities and for this purpose a table top having one tapered end is favored in order that the tubular articles, large or small, may be slipped thereover for the ironing operation. The tapered board, however, is not useful for the larger flat articles because its effective ironing area is limited to the width of the narrow end and the presence of the non-parallel sides tends to produce non-parallel ridges or creases in the work piece being ironed.

These two conflicting requirements are best solved by employing two ironing tables, one for each type of work. This, however, is not feasible in apartments and in the smaller homes because of space limitations. The best solution for this problem in the past has been to provide a plurality of hinged sections to convert the tapered board into a plain rectangle. This requires elongated hinges with special locks, or links, levers, and rotary control member and assorted gadgetry. All of these arrangements produce trouble in adjusting the combined cover and pad from the small to the larger area, unless separate covers are used for each section and this produces creases. Also, the extended part is not nearly as rigid as the principal working area of the tapered board.

An important object of the present invention is to provide a single sliding panel of novel design which will instantly convert the tapered area to a plain rectangular one and this is accomplished without hinged parts or linkages.

Another object of this invention is to provide an extensible section to give the table top with one tapered end a generally rectangular outline with full parallel sides and wherein the added part is as stable and resistant to the ironing pressures as is the main body of the table top.

A further object of the invention is the combination of a tapered ironing table top and a sliding rectangular panel and wherein the extensible panel is confined wholly within the area of the table top when said panel is in retracted position.

In the drawing:

FIG. 1 is a plan view of an ironing table top embodying the present invention and showing the sliding panel in extended position.

FIG. 2 is a side elevation thereof and showing portions of the crossed legs broken way.

FIG. 3 is a bottom plan view.

FIG. 4 is a transverse section taken on line 4—4 of FIG. 3.

The ironing table top may be formed from expanded metal or from sheet metal, the latter form being illustrated. It has a rectangular section 10 defined by opposed parallel edges 11 and a tapered section 12 defined by inwardly converging edges 14 which end in a rounded

2

section 15. The table top further has a downwardly extending flange 17 which preferably has the structural shape shown in FIG. 4 to give added reinforcement to the board. The flange also has a lower horizontal extension 18. Crossed legs are shown in broken elevation at 20 and 21 and which are pivotally mounted on shafts 22 carried by transverse struts 24 and 25. In most instances adjustment of the height of the board is effected by having one leg fixed and the other longitudinally movable. The particular leg structure, however, forms no part of the present invention.

The sliding panel which is the principal subject of the present invention is shown at 26 and has two opposed parallel edges 27 which are spaced apart a distance slightly less than the distance between the inner faces of opposed parallel flanges 17. It may further have short tapered sections 28 at the outer end and an outer transverse edge 30. A flange 31 may extend downwardly around its outer perimeter and which has a narrow horizontal flange 33 at its lower end.

The panel is mounted for sliding movement on the table top by means of cutting from flange 17, on each side of the table top, a generally rectangular slot defined at opposite ends by edges 32 at a point where longitudinal edge 11 joins diagonal edge 14, and an edge 33 which is located a few inches from rounded terminal 15 of the table top. The slot extends in a vertical direction from an upper edge 34 at the lower face of top wall 12, to an edge 35 above the lower edge of flange 17. Enough metal is left below the slot as shown at 36 to form a suitable lower support for the panel.

The channels formed along the opposed longitudinal edges of the table top by flanges 17—18 effectively support the rear section of the panel as it moves from retracted to extended position and the panel is further guided during this travel by means of mating longitudinal recesses 37 and 38 formed in the table top and panel, respectively. When the panel is in its retracted position the narrow horizontal flange 33 may rest on a portion of lower wall 36 of the slot.

While there have been described herein what are at present considered preferred embodiments of the invention, it will be obvious to those skilled in the art that many modifications and changes may be made therein without departing from the essence of the invention. It is therefore to be understood that the exemplary embodiments are illustrative and not restrictive of the invention, the scope of which is defined in the appended claims, and that all modifications that come within the meaning and range of equivalency of the claims are intended to be included therein.

What I claim is:

1. An elongated ironing table top of generally rectangular shape, formed of sheet metal, and provided at one end thereof with a tapered section of not more than half the length of the rectangular section, and means for converting the tapered section into an area of rectangular shape having substantially the same width as the rectangular section and forming an extension thereof on substantially the same plane, said table top being provided with substantially L-shaped reinforcing flanges around the opposed longitudinal edges of both sections, the flanges in the tapered section having elongated openings therein, and a sheet metal panel slidably mounted on the lower face of the rectangular section and of a width substantially the same as said section and of a length sufficient to underlie a major portion of the length of the tapered section, said panel having flanges which are enclosed by the flanges on the rectangular section when the panel is retracted, the latter flanges forming trackway to guide the panel in its sliding movement, and to retain the sliding panel in firm

surface contact with the under face of the table top, the panel passing through said elongated opening when it is moved to extended position, the outer ends of said slots being spaced from the outer end of the tapered section and forming stops for limiting outward travel of the sliding panel.

2. An elongated ironing table top of generally rectangular shape formed of sheet metal and provided at one end thereof with a tapered section of not more than half the length of the rectangular section, and means 10 for converting the tapered section into an area of rectangular shape having substantially the same width as the rectangular section and forming an extension thereof on substantially the same plane, said table top being provided with flanges around the opposed longitudinal 15 edges of both sections, the flanges in the tapered section having elongated openings therein, and a sheet metal panel slidably mounted on the lower face of the rec-

tangular section and of a width substantially the same as said section and of a length sufficient to underlie a major portion of the length of the tapered section, said panel having flanges which are enclosed by the flanges on the rectangular section when the panel is retracted, the latter flanges forming trackways to guide the panel in its sliding movement, the panel passing through said elongated opening when it is moved to extended position.
